(57) **CLAIM**

The ornamental design for a animal repellent device, as shown and described.

DESCRIPTION

FIG. 1 is a front, right and top perspective view of a animal repellent device showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The broken lines in the figures illustrate portions of the animal repellent device that form no part of the claimed design.

1 Claim, 7 Drawing Sheets
